UNITED STATES PATENT OFFICE.

GEORGE W. RAIZISS AND ABRAHAM KREMENS, OF PHILADELPHIA, PENNSYLVANIA,
ASSIGNORS TO ABBOTT LABORATORIES, OF CHICAGO, ILLINOIS, A CORPORATION
OF ILLINOIS.

SOLUTION OF ARSENOBENZENE DERIVATIVES.

No Drawing.

Application filed July 16, 1924. Serial No. 726,277.

The principal object of our invention is to produce solutions of arsenobenzene derivatives, containing the characteristic group As=As, for example, arsphenamine, which shall be stable over long periods, the toxicity of which solution is reduced to a minimum, while the therapeutic efficiency of the same is preserved. Such solutions have their chief value in the treatment of syphilis.

Attempts to prepare such stable solutions resulted previously in the lowering not only of the toxicity but also of the therapeutic efficiency. It has been claimed that simple sugars such as various hexoses: glucose, levulose, mannose, etc. are capable of preventing oxidation of the arseno group. While this finding is true, and the purpose of hindering the oxidation has been accomplished in this way and products were obtained, which are not only stable but also less toxic than the original arseno compound, the possibility has been overlooked that the therapeutic efficiency would be interfered with because of the formation of condensation products in these solutions due to the interaction of arsenobenzene compounds with the aldehyde group present in simple sugars. We believe that actual chemical combination takes place with the resulting formation of products of glucoside nature.

Should glucosides of arsenobenzene compounds be formed, the therapeutic efficiency of such products will be materially diminished.

For the purpose of preserving the full therapeutic power of the arseno compound used for making solutions, while stabilizing the same, we have discovered that disaccharides such as ordinary cane sugar, lactose and maltose, which due to their chemical constitution have not the free aldehyde group for combining with the amino groups or other available groups can diminish the toxicity as well as preserve the arseno compounds from oxidation, although without possibly entering into as firm chemical union as the more active hexoses.

With the use of disaccharides, we are able to prepare stable solutions which are not oxidized when kept in sealed ampoules. The toxicity of such solutions is materially lower than that of the original arseno compound,

while the therapeutic efficiency is not materially diminished.

Whatever slight diminution in therapeutic efficiency may be observed (per gram of arseno compound), is more than compensated for by the fact that the greatly increased tolerance, due to the reduction in toxicity, enables much larger doses to be safely employed.

We have also found that only moderate concentrations of such disaccharides are necessary for above purposes, satisfactory results having been obtained with solutions containing from 10 to 25% of the disaccharide. These solutions contain the arseno compound in concentrations ranging from 5 to 9%.

For arseno compounds such as arsphenamine or neoarsphenamine, the disaccharide, for example, may be employed in quantity as high as ten times the weight of the arseno compound, while the benefits of same are quite substantial when it is used in proportions as low as equal to the weight of the arseno product.

Furthermore, by studying the biological properties of sodium thiosulfate, we have found that it can be tolerated by lower animals intravenously in unusually large doses such as four grams per kilogram of body weight for the white rat. We further demonstrated that sodium thiosulfate, when injected intravenously just before or after the intravenous injections of arsenobenzene derivatives, has a detoxicating influence without interfering with the therapeutic efficiency. For this reason, we employ as a second detoxicating ingredient sodium thiosulfate in moderate quantities which acts also as a stabilizing agent.

In making such stable solutions of arsenobenzenes particularly of arsphenamine and its derivatives, we prepare a neutral or slightly alkaline solution of the arseno derivative in sterile distilled water in concentration ranging from 5 to 9%. In this sterile distilled water, we have previously dissolved a quantity of the disaccharide, for example, lactose, so as to obtain a solution containing from 5 to 25% of disaccharide. We also dissolve in the same solution chemically pure sodium thiosulfate in the amount

of 0.1 to 0.3 gram per ampoule (each ampoule contains one therapeutic dose of arsenobenzene compound varying from 0.2 gram up to a maximum of 0.9 gram). When such solution containing the arsenobenzene derivative, disaccharide, and sodium thiosulfate, is obtained, it is introduced into glass ampoules, which are then attached to a high vacuum system for the purpose of removing oxygen. The ampoules are then sealed by means of a hot flame with such precautions that no air enters the glass container. Such solutions are stable and ready for intravenous injection without further manipulation by the physician.

The described details being merely illustrative of my invention, it will be understood that the scope of the invention should be determined by reference to the appended claims, said claims being construed as

broadly as possible, consistent with the state of the art.

We claim as our invention:

1. As a new article of manufacture, a solution of an arsenobenzene derivative, containing the characteristic group As=As, containing a sugar and sodium thiosulfate as stabilizing and detoxicating ingredients. 25

2. As a new article of manufacture, a therapeutic solution of an arsenobenzene derivative, containing a disaccharide and sodium thiosulfate as stabilizing and detoxicating ingredients. 30

3. As a new article of manufacture, a solution or arsenobenzene derivative, containing sodium thiosulfate as a stabilizing and detoxicating ingredient. 35

GEORGE W. RAIZISS.
ABRAHAM KREMENS.
